UNITED STATES PATENT OFFICE.

LANDRUM H. PELPHREY, OF GIRARD, KANSAS, ASSIGNOR OF FORTY-FIVE ONE-HUNDREDTHS TO U. G. PELPHREY, OF MULBERRY, KANSAS.

INLET-VALVE CASING.

1,371,110.

Specification of Letters Patent.

Patented Mar. 8, 1921.

Application filed October 21, 1919. Serial No. 332,352.

To all whom it may concern:

Be it known that I, LANDRUM H. PELPHREY, a citizen of the United States of America, residing at Girard, in the county of Crawford and State of Kansas, have invented new and useful Improvements in Inlet-Valve Casings, of which the following is a specification.

The object of the invention is to provide means in the nature of a protector for the inlet or feed end of the suction pipe of a pump of the type used in connection with drainage work in mines and adapted to be used in lieu of a globe valve and also of a check valve and strainer for preventing the induction of solid objects into the suction pipe of the pump.

Furthermore it is the object to provide a device for the purpose indicated which can be constructed at a comparatively small cost and which will operate automatically in feeding the pump, maintaining itself in proper relation to the surface of the water in the mine and dispense with the services of a helper or pump man ordinarily employed in this connection.

Further objects and advantages of the invention will appear in the course of the following description of a preferred embodiment, it being understood that changes in form and proportion may be resorted to within the scope of the claims without departing from the principles involved.

In the drawing:

Figure 1 is a side view of the feed nozzle.

Fig. 2 is a sectional view of the same.

The casing of the device preferably comprises the detachable coupling member 10 and strainer member 11, the former of which is provided with a threaded terminal 12 for engagement with the end of the suction pipe of the pump (not shown) while the latter is connected with the former by a threaded joint 13 produced by forming an exteriorly threaded collar 14 on the strainer member to engage a corresponding opening in the wall of the coupling member. At its inner end this collar is constructed to form a valve seat 15 for the reception of the check valve 16 when not unseated by the suction of

the pump which acts obviously in the direction indicated by the arrow in Fig. 2. The stem 17 of the valve extends through the valve seat and a guide 18 at the outer side of the strainer member for attachment to a float 19 by which the valve is normally held closed and the casing maintained at a proper depth in the water in which it is submerged. The float serves obviously to hold the casing in an upright position with the perforated wall 20 of the strainer uppermost and near the surface of the water so as to avoid the induction of solid matter near the bottom and thus prevent the choking of the perforations. Obviously for cleansing purposes the members of the casing may be readily disconnected, and when the pump is not in operation the check valve is held seated by the effect of the float thereon opposed by the weight of the casing.

What is claimed is:

1. An inlet valve casing for suction pipes having a perforated strainer wall, a check valve seatable between the strainer wall and the outlet of the casing, and a float connected with the valve for normally maintaining the same seated in opposition to the direction of suction through the casing.

2. A protector for the suction pipes of pumps having its casing provided at the inlet end with a screen and at an intermediate point, between the inlet and outlet ends with a valve seat, and a float actuated check valve mounted for seating movement in a direction toward the inlet end of the casing.

3. A device for the purpose indicated having a casing provided with detachable coupling and strainer members of which the former is provided with means for engaging a suction pipe, and a float actuated valve movable in the direction of flow through the casing and seatable toward the inlet end thereof, the stem of said valve extending through and beyond the strainer end of the casing.

4. A device for the purpose indicated having a casing comprising detachable coupling and strainer members of which one is provided with a threaded collar for engagement with a corresponding recess in the other, a

valve seat being provided in said collar and a guide being provided in the strainer member in axial alinement with said collar, and a float actuated valve for engagement with 5 said seat and adapted to close in opposition to the flow of liquid through the casing and

having its stem extended through said guide, the strainer member being provided with liquid inlet openings in the portion of 10 its wall between said collar and guide.

In testimony whereof I affix my signature.
LANDRUM H. PELPHREY.
